(57) **CLAIM**

The ornamental design for a cap of cartridge for component extraction, as shown and described.

DESCRIPTION

FIG. 1 is a perspective view of the top, front and right side of the cap of cartridge for component extraction;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view thereof at 8—8 in FIG. 3;

FIG. 9 is a cross-sectional view thereof at 9—9 in FIG. 3;

FIG. 10 is a cross-sectional view thereof at 10—10 in FIG. 3;

FIG. 11 is a front elevational view thereof with the circular filter element seen in FIGS. 2, 8, 9, 10, and 13 removed in order to depict the inner structure of the cap of cartridge for component extraction;

FIG. 12 is a cross sectional view along line 12—12 of FIG. 4, with the circular filter element removed as in FIG. 11; and,

FIG. 13 is an exploded perspective view thereof showing the circular filter element and remaining portion of the cap of cartridge for component extraction separated.

The portions shown in broken lines are for environmental purposes only and form no part of the claimed design.
